UNITED STATES PATENT OFFICE

2,614,728

REPEAT VALVE SHUTOFF MECHANISM

Earl M. Kreidler, Pittsburgh, Pa., assignor to
Rockwell Manufacturing Company, Pittsburgh,
Pa., a corporation of Pennsylvania

Application June 6, 1949, Serial No. 97,353

8 Claims. (Cl. 222—20)

1

This invention relates to liquid measuring apparatus and is particularly directed to such apparatus for filling each of a succession of containers with a predetermined quantity of liquid and wherein the flow of liquid is stopped automatically as soon as each container has been filled.

It is a major object of my invention to provide a repeating container-filling apparatus containing novel shut-off control mechanism in association with a meter driven register.

It is a further object of my invention to provide fluid measuring apparatus wherein a novel latch mechanism set by nozzle operation is adapted to be tripped by the register when a predetermined quantity of liquid has been passed through the nozzle.

A further object of the invention is to provide a novel re-set mechanism for the register control latch of a liquid measuring apparatus.

A further object of the invention is the use of positive gear drive in a predetermining register control, correlated replaceable gear sets being available for setting the register to trip the latch at different exact predetermined quantities of delivery.

Further object of the invention will appear as the description proceeds in connection with the appended claims and the annexed drawings wherein:

Figure 1 is a side elevation assembly of a meter and register in coupled relation to the filling nozzle controlled thereby, according to a preferred embodiment of the invention;

Figure 2 is a top plan view of the nozzle assembly, with the parts in nozzle open position;

Figure 3 is a top plan view of the latching, tripping and resetting mechanism, part of the casing being broken away and in section;

Figure 4 is a side elevation of the mechanism of Figure 3, with the front cover plate removed to show the cooperating latch elements and the reset cam;

Figure 5 is a fragmentary elevation externally of the cover plate, illustrating the manner of indexing the re-set cam;

Figure 6 is a section in elevation illustrating the register and latch trip drive within the casing;

Figure 7 is another section through the casing illustrating the re-set cam shaft and associated drive mechanism;

Figure 8 is a sectional plan view illustrating the mounting of the cam controlled latch member;

2

Figure 9 is an axial sectional view of the re-set cam shaft illustrating particularly the one-way clutch connection between the cam and the shaft;

5 Figure 10 is an end elevation of the nozzle controlled by the register;

Figure 11 is an axial section through the nozzle of Figure 10; and

10 Figure 12 is a side elevation of the top of the nozzle of Figure 9.

Referring to Figure 1, a piston or like meter unit 11 adapted to receive liquid to be measured through an inlet (not shown), which liquid may be either pumped or delivered by gravity to the meter, has an outlet 12 connected by a flexible conduit 13 to a nozzle unit 14, later to be described in more detail. The meter 11 may be any suitable type of fluid flow measuring meter, although preferably it is of the opposed piston type. Secured to the upper part of the meter 11 is a register and nozzle control assembly comprising an intermediate drive mechanism housing 15 upon which is secured a mainly cylindrical register casing 16. The intermediate housing 15 contains variable drive gear mechanism between the meter and register having means for controlling the meter output in accord with physical characteristics of the liquid passing through the meter. To this end, I may provide within the housing 15 suitable combined temperature and specific gravity compensation devices connected to vary the speed at which the meter output shaft drives the register. These compensation devices are not shown but may be the same as disclosed in United States Letters Patent to Marsh No. 2,438,934 issued April 6, 1948, to which reference is made for any detail necessary to understand this invention.

In any event, meter 11 drives a pinion 17 at the 40 upper out-put end of housing 15 at a speed which is proportional to the flow of fluid through the meter, which speed may be compensated in accord with the temperature and/or specific gravity of the metered liquid.

45 The entire bottom of casing 16 is closed by a solid base plate 18, the two being secured together by a plurality of screws (not shown) disposed about their adjacent peripheries. All of the latch reset and trip mechanism within casing 16 is mounted on base plate 18, during assembly, and the casing 16 may be readily removed from the base plate to expose the mechanism for repair without dismounting the latter from plate 18.

50 At one side, casing 16 is formed with parallel

integral extensions providing a flat wall 19 having a large rectangular opening 20 normally closed by a thin plate 21 secured to wall 19 as by screws 22. The curved wall of casing 16 is formed substantially diametrically opposite wall 19 with a generally rectangular opening 23 closed normally by a thin plate 24 secured to the casing as by screws 25. The purpose of these openings will appear later.

At its top, casing 16 is closed by an integral wall 26 except for a central opening 27 in said wall which is covered by mounting thereabove a conventional register mechanism housing 28 containing the usual visible counter from which the accumulated amount of fluid that has been delivered by the meter may be noted at any time. Mechanism housing 28 is secured to casing 16 as by a plurality of bolts 29 passing through a flange on housing 28 and into suitable threaded holes 30 in wall 26. Preferably the casing 16 is mounted upon housing 15 as by a plurality of long bolts 31 that have their heads seated in suitable counterbores in wall 26 and extend down through the interior of casing 16 and through base plate 18 into threaded bores in housing 15 as indicated in Figure 1. The register itself is preferably a conventional calibrated counter and need not be further described.

Depending from register housing 28 is a shaft 32 carrying a gear 33 disposed within the opening 27 and in constant mesh with a gear 34 driven from the meter and compensating mechanism as will appear. The entire register casing 28 with exposed gear 33 at the bottom is a separate unit removable from the casing 16 by removing bolts 29.

Referring to Figures 1, 6 and 7, gear 17 driven by the meter and compensating mechanism is meshed with a gear 35 removably secured to a vertical shaft 36 that extends upwardly through a bore 37 in an integral internal boss 38 upstanding from plate 18 into the interior of casing 16. Shaft 36 is journaled in bushings 39 that line bore 37, and below bore 37 shaft 36 has a gear 40 secured thereto, as by a set screw 41. The upper end of shaft 36 has a worm 42, and shaft 36 is maintained from axial movement within boss 38 by abutment of gears 40 and worm 42 with opposite ends of the boss 38. If shaft 36 is to be removed from the boss, it is only necessary to remove gear 35 and loosen screw 41 and pull the shaft upwardly through the boss.

Boss 38 is provided with an integral upward extension at one side containing a bore 43 parallel to bore 37 and lined with bushings 44 for journaling a vertical shaft 45 parallel to shaft 36. A gear 46 constantly meshed with gear 40 is secured upon the lower end of shaft 45 by a set screw 47. Above the boss, shaft 45 is provided with an enlarged flange 48 abutting the top of the boss which together with gear 46 prevents axial displacement of the shaft. Above this flange, shaft 45 has non-rotatably secured thereto the gear 34 which is constantly meshed with the register counter drive gear 33.

In this manner I provide a direct positive drive through the intermediate casing from the meter driven gear 17 to the register drive gear 33 so that the counter within housing 28 will be driven at all times regardless of the operation of the reset mechanism to be described. Preferably the gears are of such size that the speed of shaft 32 is the same as that of the shaft on which gear 17 is mounted.

Referring to Figure 3 and 6, worm 42 is constantly meshed with a worm gear 49 secured

non-rotatably upon a horizontal shaft 50 journaled at opposite ends upon spaced bosses 51 and 52 upstanding integrally from base plate 18 into the interior of casing 16. Suitable removable spacers may be provided along shaft 50 for preventing its axial movement after assembly. On the side of boss 51 opposite gear 49, shaft 50 has removably secured thereto, as by a set screw 53, a gear 54 constantly meshed with a gear 55 removably secured, as by set screw 56, upon the end of a shaft 57 that extends through boss 51, above the worm 42 and then through another boss 58 that also upstands integrally from plate 18 into the interior of casing 16.

Shaft 57 and its assembly are illustrated best in Figure 9. Shaft 57 extends through the boss 58 and terminates within the opening 20 of casing wall 19. A collar 59 is fixed to this end of shaft 57, as by pin 60 thereby providing an enlarged head for the shaft. Bushings 61 and 62 journal and support shaft 57 on bosses 51 and 58.

An integral cam member 63 is freely rotatably mounted on shaft 57 and formed at its outer end with a bore 64 at the bottom of which is a shoulder 65 against which the enlarged head of 57 is seated. Bore 64 is threaded at its outer end beyond head 59 and closed by a screw threaded closure cap 66 which may be removed when separation of the cam and shaft is desired.

A spacer block 67 removably secured to shaft 57 as by set screw 68 abuts the inner side of boss 58 to limit axial displacement of shaft 57 and prevent binding of gear 55 during operation.

At the other side of boss 58, shaft 57 is formed with a longitudinal slot 69 and surrounded by a separate cam hub sleeve 70 having a radial flange 71 intermediate its ends. Outwardly of flange 71, sleeve 70 is formed with a shallow annular groove 72 and a cylindrical surface 73 smaller than flange 71. A removable key element, such as a set screw 74, extends through sleeve 70 into slot 69 to prevent relative rotation of sleeve 70 and shaft 57 but to permit some axial movement of the sleeve along the shaft.

Cam member 63 is formed at its inner end with a radial shoulder 75 beyond which is a reduced cylindrical surface 76 of the same size as the cylindrical portion 73 of separate cam hub sleeve 70, and a shallow annular groove 77 is formed in cam 63 at the base of shoulder 75. A compressed coil spring 78 extends between the cam and the spaced cam hub with its end coils locked in grooves 72 and 77. This spring is stiff enough so that the cam and cam hub may be united through this spring connection only as a sub-assembly. A thin metal sleeve 79 is provided with its inner end pressed onto a shoulder on cam 63 and overlying the portion of spring 78 attached to cam 63.

One function of compression spring 78 in this assembly is to react against stationary boss 58 through hub sleeve 70 and thereby urge cam 63 into tight frictional engagement with head 59 of shaft 57. Spring 78 also functions as a one-way clutch between shaft 57 and cam 63. The spring is coiled in such direction that when cam 63 is turned in a clockwise direction as viewed in Figure 4 the spring coil will wrap about and bind upon the cylindrical surfaces 73 and 76 of the cam and hub sleeve respectively, thereby preventing relative rotation between the cam and shaft, but when the cam is turned in a counter-clockwise direction the tendency of the spring is to unwind thereby permitting relative rotation

between cam 63 and shaft 57 for re-set purposes,

as will appear in further description of the invention. Slippage between the spring and the cam parts and between the cam 63 and the shaft also permits this relative rotation.

Referring now to Figures 3 and 4, boss 59 is formed at a lower level than shaft 57 with a lateral projection 81 having a stationary horizontal pivot pin 82 projecting therefrom parallel to the axis of shaft 57. A latch bar 83 is freely pivoted on pin 82, being axially retained thereon by a stop collar 84. Latch bar 83 is constantly biased clockwise in Figure 4 by a tension spring 85 anchored at opposite ends on latch bar 83 and stationary boss 58. Movement of latch bar 83 in clockwise direction is limited by engagement of a dog 86 on the latch bar with a stationary stop pin 87 upstanding from base plate 18.

A support block 88 upstanding from the floor of plate 18 carries a horizontal stationary pivot pin assembly 89 on which is freely journaled a second latch bar 91 having a bifurcated upper end bridged by a pin 92 over which is pivotally hooked the end 93 of a fitting 94 secured upon one end of a flexible cable 95 that extends from casting 16 to nozzle 14 as will appear. The adjacent lower ends of latch bars 83 and 91, which will engage each other during operation, are provided with welded insert blocks 96 and 97 of some hard wear resistant material like tungsten carbide or hardened steel to reduce wear in the assembly and maintain accuracy in operation.

As illustrated best in Figure 4, cam member 63 is integrally formed with a lateral cam projection 98 having a curved surface 99 adapted to wipingly engage a horizontal pin 100 projecting laterally from the upper part of latch bar 83, and the operation of this cam will presently be described. Cam projection 98 is also formed with a face 101 adapted to engage pin 100 during reset as will also be later described.

Flexible cable 95 extends through a sheath 102 which is secured to a nozzle attachment fitting 103 at its remote end. The register end of sheath 102 is threaded at 104 for mounting an internally and externally threaded coupling 105 that is threadedly secured in a threaded bore 106 in the side of casing 16. When coupling 105 is drawn tight, it secures sheath 102 rigidly with casing 16, and the flexible cable 95 is of course free to slide within the sheath. At the other end of the cable where it projects from sheath 102, an enlarged head button 107 is fixed upon the cable 95. A coiled compression spring 108 extends between head 107 and fitting 103, being piloted on a boss 109 rigid with head 107.

In the assembly illustrated in Figure 1, fitting 103 is rigidly mounted within a tubular bracket 110 secured to the body of nozzle 14 as by screws 111 (Figure 2). Spring 108, when compressed in nozzle open position as in Figures 1 and 2, constantly tends to move head 107 to the left in Figure 4, thereby tending to pull latch bar 91 counterclockwise toward the dotted line position of Figure 4.

Referring to Figures 1, 2, 10, 11 and 12 for nozzle construction, nozzle 14 comprises a body member 112 to the bottom of which is fixed a seat member 113 having a depending conduit portion 114 adapted to enter a hole in the barrel or other container to be filled. A valve member 115, having a flexible annular seat 116 adapted to seat with member 113, is secured rigidly upon an upstanding rod 117 slidably mounted in a bore 118 in the upper wall of the body 112. A heavy coil compression spring 119 reacts between the top wall of the body and the valve 115 and constantly

urges valve 115 toward its lower closed position.

A side opening 120 is provided for communicating the conduit 13 with the interior of nozzle body 112. Valve 115 is shown in open position in all of the Figures 1, 2, 10 and 11.

The upper end of body 112 is formed with an upstanding cylindrical boss 121 within which is mounted a gland assembly 122 slidably surrounding rod 117. An operating head 123, which also serves as a cap for closing the top of boss 121, is provided upon its lower edge with a plurality of, preferably three, inclined equally spaced cam faces 124 that each intersect a vertical face 125 at one end and intersect a planar surface 126 on the bottom of the cam head and perpendicular to the axis of rod 117 at the other end. Preferably the angle of each face 124 is about 60° relative to the valve axis. A planar ledge or surface 127 on body 112 also perpendicular to the valve axis surrounds the bottom of boss 121. A number of stationary pins 128, corresponding in number and location to the inclined cam surfaces 124, upstand from ledge 127. These pins support head 123 when the valve is in open position, and they are disposed within the recesses formed by faces 124 and 125 when the valve is in the closed position illustrated in Figure 12.

A lock nut assembly 129 is mounted upon the threaded upper end of rod 117 where the rod projects slidably through a bore 130 in the upper wall of head 123. Cam head 123 and rod 117 are preferably relatively rotatable although not necessarily so. Spring 119, acting through rod 117 and nut assembly 129 urges cap 123 and body 112 axially together. A radial lug 131 integral with head 123 is provided for engaging cable end button 107 during operation, and a radial arm 132 is secured to head 123 for manually turning it about boss 121 to open the valve. The nozzle body is also provided with a handle 133 for the operator to shift the nozzle from one container to another.

Operation

Assuming that meter 11 is connected to a source of liquid to be measured, the operator places conduit 114 in a container to be filled and rocks cam head 123 (clockwise in Figure 2) to the full line position of Figure 2. Engagement of lug 131 with button 107 slides flexible cable 95 to the right in Figure 4 thereby rocking latch bar 91 from the illustrated dotted line position to the full line position of Figure 4 and permitting spring 85 to rock the cooperating latch bar 83 clockwise into the full line position of Figure 4 where it is arrested by pin 87 which serves as a positive stop to maintain latch bar 91 in the full line set position. Spring 108 is compressed between head 107 and relatively stationary sleeve 103 during this operation, and the valve 115 is opened because rod 117 is displaced upwardly with the cam head as the latter rides upwardly on pins 128. As cam head 123 rotates clockwise in Figure 2, it bears on ledge 127 until inclined surfaces 124 engage the rounded head pins 128 which cam the head upwardly, sliding it along boss 121 against the pull of spring 119 which is thereby further compressed. When the head has rocked sufficiently to raise valve 115 into open position, further rocking continues with surface 126 bearing on the tops of pins 128 until the full line position of Figure 2 is attained. Then the operator releases arm 132.

At this point compressed spring 119 will pull downwardly on head 123 but pins 128 maintain the head raised and the valve open. Spring 108,

which has been also compressed during the operation of opening the valve, reacts against button 107 but the cable 95 is now latched and held against the action of spring 108 by the mechanism within casing 16. Friction and the downward pull of spring 119 prevent accidental closing of the valve. The proportions are such that spring 108 may effect a small return rocking movement of the head when the operator releases arm 132, to take up play in the latching mechanism, but this is not enough to rotate the head back far enough for pins 123 to enter the recesses defined by surfaces 124. When the parts are in latched position as illustrated in Figure 4, wear tip 97 of latch bar 91 is engaged with the wear tip 96 on the lower end of latch bar 83, whereby after the operator releases arm 132 latch bar 83 is a stop for preventing spring 108 from shifting cable 95 to rock cam head 123 counterclockwise with respect to its full line position of Figure 2. In Figure 4, the dotted line position of cam projection 98 wherein its face 101 is substantially in contact with pin 100 is the relation that these parts occupy when the latch bars are cocked as above described. The arrow in Figure 4 shows the rotation of the cam during the container filling operation.

The valve 115 being now open, liquid to be measured flows through meter 11 and conduit 13 and through the open valve into the container. Passage of the liquid through the meter is effective to rotate drive pinion 17 which drives the counter in register 28 through gear 35, shaft 36, gear 46, gear 46, shaft 45, gear 34, gear 33 and shaft 32. At the same time shaft 57 is rotated clockwise, as viewed in Figure 4, from the starting position with face 101 in engagement with pin 100. Rotation of shaft 36 by the meter as above described also causes rotation of shaft 56 through the worm and gear combination 42 and 49, and this in turn produces rotation of shaft 57 through the meshed pinion gear combination 54 and 55. Since key 14 is disposed in slot 69, the cam assembly will rotate with shaft 57.

As the barrel or other container being filled nears its capacity, the cam face 99 of projection 98 will slowly approach the full line position illustrated in Figure 4 wherein it contacts pin 100. Contact of moving cam face 99 with pin 100 will cause counterclockwise rocking of latch bar 83 against the pull of spring 85 to thereby move latch bar 83 to the dotted line position of Figure 4 and thereby release latch bar 91 and enable the spring 108 to expand and rotate cam 123 toward the dotted line position illustrated in Figure 2. As soon as the cam head has rocked far enough to locate the recesses 124, 125 over pins 123, spring 119 takes over and completes the closing movement of the valve quickly. The nozzle parts assume the position of Figure 12 when closed. This trip action of spring 108 and the follow up action of spring 119 quickly closes valve 115 as soon as the correct amount of fluid has been supplied to the container through the nozzle.

The ratio of the number of teeth of gear 54 to the number of teeth of gear 55 predetermines the latch trip action and thus determines the amount of fluid delivered to the nozzle. In the invention I have provided different cooperating sets of gears 54 and 55 with suitable number of teeth for rotating shaft 57 at such different rates as to provide delivery of different predetermined numbers of gallons to the nozzle. For example 50, 51, 52, 53 or 55 gallons may be predetermined

as desired according to the capacity of the container to be filled. Access to the interior of the casing for replacing these gears may be gained simply by removing screw 25 and cover plate 24 without disturbing any of the other mechanism. These sets of gears 54, 55 provide a positive drive for the shaft 57 which is much more reliable than hitherto used chain drives for the same purpose. In the chain drive, it is impossible to obtain a chain in which the links are all of the same size and hence it was difficult to reproducibly set it for exact predetermined quantities because it was not always possible to remove links of the same length. Furthermore, with a gear drive, a much wider range of calibration of the device is obtained in that much smaller delivery quantities can be predetermined in the meter with greater accuracy. For example, with the gear drive and suitable selection of gears I can optionally deliver quantities in one-half gallon steps from a minimum of one-gallon to 50 or more gallons with amazing accuracy.

The dotted lines in Figure 4 illustrate the positions that latch bars 83 and 91 occupy after having been tripped by the cam. Latch bar 91 has been rocked until its tip serves as a stop to limit rocking of bar 83 by spring 85.

When the nozzle is reopened, thereby rocking latch bar 91 clockwise, its tip 97 simply slides along tip 96 until it clears latch bar 83 and permits spring 85 to shift the latter into its full line position.

The relation of the parts is such that rotation of shaft 57 and cam 63 should cease at the end of each container filling operation when cam projection 98 has just passed the pin 100 with cam face 101 substantially in contact with upper side of pin 100. The purpose of the one-way clutch between cam 63 and shaft 57 is to permit reset of the cam to this initial position and theoretically it is necessary only at the beginning of a series of filling operations and it is not necessary to reset after each container is filled because of the relation of parts just mentioned.

The reset operation is accomplished by rotating cam 63 counterclockwise (Figure 4) until stopped by the pin 100. The gearing beyond shaft 57 locks the shaft against rotation during this operation. As illustrated in Figure 5, an index line 134 is preferably provided on the outer face of plate 21 to coact with an index line 135 on the front of cam 63 where the latter projects through plate 21 to provide proper reset for the cam. When the cam is set as indicated in Figure 5, cam surface 101 is substantially in contact with pin 100. The cam will stop with these index lines in alignment after each container is filled.

This invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a system for repeatedly dispensing a predetermined quantity of liquid, a meter driven by the liquid to be dispensed, a register assembly driven by said meter, an outlet conduit for said meter, a nozzle on the conduit containing a flow

control valve, a motion transmitting member extending between said register assembly and said nozzle, means for manually actuating said valve to open said valve, having a part coacting with said motion transmitting member to shift said member in the movement of the valve to open position, means for latching said shifted member, resilient means biasing said member to normal position and energized during said opening of the valve to urge said member in a direction to effect closure of said valve, and means driven by the meter for tripping said latching mechanism to permit said resilient means to actuate said member and transmit motion to said valve actuating means in valve closing direction to effect closure of the valve after a predetermined quantity of liquid has been dispensed through said nozzle.

2. In a liquid dispensing assembly, a meter, a conduit connected to the meter outlet, a nozzle on the conduit, a valve in the nozzle, a valve operating head rotatable on said nozzle, an axially movable flexible cable connected at one end to said nozzle, means carried by said head coacting with said cable to shift the cable in one direction in the valve opening movement of said head, energy storing means rendered effective in the valve opening movement of said head to shift said cable in the opposite direction and transmit rotation to said head in valve closing direction, a register assembly adjacent said meter, means in said register assembly operatively connected with the other end of said cable to latch said cable when the valve is opened, and meter operated means for tripping said latching means when a predetermined quantity of liquid has passed through said valve.

3. In the liquid dispensing assembly defined in claim 2, said energy storing means comprising a spring compressed between said cable and the nozzle during said valve opening operation adapted to actuate said cable to rotate said head toward valve closed position when said latching means is tripped.

4. Repeating valve shut-off mechanism comprising cooperating latch members, one of which is operatively connected to a valve control member, a meter driven shaft, a cam on said shaft adapted upon rotation of said shaft in one direction to engage the other of said latch members for tripping the latch to effect closure of the valve, and a direct one-way driving couple between said shaft and cam permitting rotation of said cam

on said shaft in the direction opposite said one direction to reset said mechanism at the beginning of a series of container filling operations.

5. The repeating valve shut-off mechanism defined in claim 4 in combination with a casing through which the cam projects to provide a reset knob, and reset index means on the casing and knob.

6. In a liquid dispensing apparatus including a meter, a conduit connected at one end to the meter outlet and having a nozzle at its other end and a valve in said nozzle; means controlling the opening and closing movements of said valve comprising a rotatable member manually operable in one direction to open said valve, a motion transmitting element having means at one end yieldably interposed between said nozzle and member and rendered effective by said member to move said element and transmit motion to said member in the opposite direction to close the valve, means for latching said element and restraining said yieldable means against effective operation, and meter operated means for tripping said latching means when a predetermined quantity of liquid has passed through the valve.

7. In a liquid dispensing apparatus as defined in claim 6, said latching means comprising a pivotally mounted member pivotally connected to the other end of said motion transmitting element, and a pivoted spring biased latch lever directly coacting with said member.

8. In a liquid dispensing apparatus as defined by claim 7, said meter operated means comprising a rotatable member having a cam lug adapted to be positioned with respect to said latch lever by manual rotation of said member in one direction, and means drivingly connecting said member with a meter driven shaft to rotate said member in the opposite direction and trip said latch lever to release position.

EARL M. KREIDLER.
